US0D1031867S

(12) **United States Design Patent** (10) **Patent No.:** **US D1,031,867 S**
(45) **Date of Patent:** **** Jun. 18, 2024**

(54) **PLUSH TOY**

(71) Applicant: **Yeehoo Corporation**, San Pedro, CA (US)

(72) Inventor: **Huiting Wu**, San Pedro, CA (US)

(73) Assignee: **Yeehoo Corporation**, San Pedro, CA (US)

(**) Term: **15 Years**

(21) Appl. No.: **29/930,600**

(22) Filed: **Mar. 1, 2024**

(51) LOC (14) Cl. **21-01**

(52) U.S. Cl.

USPC **D21/576; D6/597**

(58) **Field of Classification Search**

USPC D6/597, 598, 599, 601, 604; D21/525,

D21/576

CPC A47G 9/10; A47G 9/1045; A49G

2009/1018; A63H 3/02; A63H 3/08;

A63H 3/12; A63H 3/14
